DESIGN FOR A DISPLAY COUNTER

Ferdinand G. Welke, San Francisco, Calif., assignor to Shell Oil Company, Inc., San Francisco, Calif., a corporation of Virginia

Application October 15, 1945, Serial No. 122,832

Term of patent 7 years

(Cl. D80—9)

To all whom it may concern:

Be it known that I, Ferdinand G. Welke, a citizen of the United States and a resident of the city and county of San Francisco, State of California, have invented a new, original, and ornamental Design for a Display Counter, of which the following is a specification, reference being had to the accompanying drawing, forming part thereof.

Figure I is an isometric view showing the front

and side of a display counter showing my new design.

Figure II is an isometric view showing the rear and side of a display counter showing my new design.

I claim:

The ornamental design for a display counter, as shown.

FERDINAND G. WELKE.
